UNITED STATES PATENT OFFICE

168,316

ICE-CREAM FREEZER

Dudley C. Pulliam, Chicago, Ill., assignor to Chicago Electric Manufacturing Company, Chicago, Ill., a corporation of Illinois

Application December 2, 1950, Serial No. 13,239

Term of patent 14 years

(Cl. D67—2)

To all whom it may concern:

Be it known that I, Dudley C. Pulliam, a citizen of the United States, residing in Chicago, Cook County, State of Illinois, have invented a new, original, and ornamental Design for an Ice Cream Freezer, of which the following is a specification, reference being had to the accompanying drawing forming a part thereof:

Fig. 1 is a plan view of an ice cream freezer showing my new design;

Fig. 2 is a side view thereof; and

Fig. 3 is a fragmentary side view thereof.

The dominant features of the design reside in the portions shown in full lines.

I claim:

The ornamental design for an ice cream freezer, as shown and described.

DUDLEY C. PULLIAM.
